US0D1057756S

(12) **United States Design Patent** (10) **Patent No.:** **US D1,057,756 S**
Thornberg (45) **Date of Patent:** **** Jan. 14, 2025**

(54) **DISPLAY SCREEN OR PORTION THEREOF WITH GRAPHICAL USER INTERFACE**

(71) Applicant: **Terry Thornberg**, Bethel, MN (US)

(72) Inventor: **Terry Thornberg**, Bethel, MN (US)

(73) Assignee: **FABSYSTEMS, INC.**, Bethel, MN (US)

(**) Term: **15 Years**

(21) Appl. No.: **29/856,807**

(22) Filed: **Oct. 17, 2022**

Related U.S. Application Data

(62) Division of application No. 29/731,800, filed on Apr. 17, 2020, now Pat. No. Des. 967,156, which is a division of application No. 29/643,278, filed on Apr. 6, 2018, now Pat. No. Des. 884,008.

(57) **CLAIM**

The ornamental design for a display screen or portion thereof with graphical user interface as shown and described.

DESCRIPTION

The sole FIGURE is a front view of a display screen or portion thereof with graphical user interface, according to the claimed design.

The outermost broken line illustrates a display screen and forms no part of the claimed design. The remaining broken lines illustrate portions of a graphical user interface and form no part of the claimed design.

1 Claim, 1 Drawing Sheet
